UNITED STATES PATENT OFFICE.

EDWARD D. FELDMAN, OF NEW YORK, N. Y., ASSIGNOR TO PENCIL MECHANISM CORPORATION, A CORPORATION OF NEW YORK.

MAGAZINE LEAD PENCIL.

Application filed March 3, 1924, Serial No. 696,666, and in Germany November 12, 1923. Renewed November 2, 1928.

This invention relates to mechanical pencils and particularly to mechanical pencils of the type wherein the lead is advanced by a step-by-step movement.

5 An object of the invention is to provide a step-by-step mechanical pencil which is simple and sturdy of construction and which may be readily and economically manufactured and assembled.

10 Another object is to provide, in a step-by-step mechanical pencil, means whereby a lead may be advanced with ease and certainty.

Another object is to provide a step-by-step mechanical pencil which may be operated and 15 used with relatively small danger of breaking the lead.

Other objects of the invention will in part be obvious and will in part appear herein-after.

20 The present application is directed to certain improvements over the inventions described and claimed in the copending application of Alfred Woelm, Ser. No. 588,688, filed September 16, 1922, the copending application of Alfred Woelm, Ser. No. 180,000, 25 filed March 31, 1927, constituting a division of said Woelm application, Ser. No. 588,688, the copending application of Edward D. Feldman, Ser. No. 596,309, filed October 23, 1922, and the copending application of 30 Alfred Woelm, Ser. No. 642,858, filed June 1, 1923.

The invention accordingly comprises an article of manufacture possessing the features, 35 properties, and the relation of elements which will be exemplified in the article hereinafter described and the scope of the application of which will be indicated in the claims.

For a fuller understanding of the nature 40 and objects of the invention reference should be had to the following detailed description taken in connection with the accompanying drawings, in which:

Figure 1 is a longitudinal section of a pencil embodying the invention, showing the parts in normal writing position;

Fig. 2 is a partly sectional view showing the parts in advanced position; and

Fig. 3 is a partly sectional view taken at 50 right angles to Fig. 2 and showing the parts in advanced position.

The same reference characters refer to the same parts throughout the several views.

In the drawings the numeral 1 designates

the casing of the pencil which has the usual 55 pointed portion 2. In the casing 1, is located a second, inner tube 3, adapted to be displaced by, and which is connected in any suitable manner with, the cap 4. The numeral 5 designates the lead guide tube which is fastened 60 in a plug 6, and at its lower end are formed springy tongues 7. The upper end of the tube 5 is enlarged in any suitable manner, as by fastening thereto a plate 19, so as to substantially close the tube 3, and form a bottom 65 for the lead compartment or magazine. The plug 6 is fastened into the pointed portion of the casing part in any suitable manner.

On the guide tube 5, and above the plug 6, 70 is movably disposed a plate or disk 8, which plate is normally pressed upwards against the propelling device 10, by a spring 9, and holds the gripper jaws 11 in closed position by reason of a cone shaped hole or annular 75 recess formed in the upper surface of the disk 8, the sides of which recess contact with the inclined sides of the gripper jaws 11.

The gripping propelling device consists of two outwardly springing legs 10, projecting 80 downward from a connecting piece 14, attached to a sleeve 15 guided in a collar 16 fastened to the inner tube 3. The free ends of the legs 10 are preferably formed substantially as illustrated, the portion 11 converging 85 inwardly to form the before mentioned inclined sides of the gripper jaws. The jaws are preferably curved so as to fit the lead strips. Between the straight and the converging portions of the legs 10—11, the legs 90 are curved outwards to form cams 30.

The grippers 11 are adapted to enter through the slots 12 in the guide tube 5 so as to grip and hold a lead strip therein while the parts are at rest and during the forward 95 or downward movement of the feeding mechanism.

The grippers 10, 10, may pass through slots in a piece 13 fastened on the guide tube 5 so as to hold them in alignment with the slots 100 12. The piece 13 also acts as a stop or abutment to limit the downward movement of the sleeve 15. On the sleeve 15 is fastened a disk 17 adapted to limit the downward movement of the collar 16 thereon, and between the disk 17 and the bottom of the collar 16 is a spring 105 18 under slight compression.

The lower end of the tube 3 is provided

with tongues or other suitable projections 20, 21, adapted to contact with the plate or disk 8 before the sleeve 16 reaches its downward limit of travel, and to force said disk downward against the tension of the spring 9, a distance sufficient to release the grippers and permit them to release their grip on the lead strip.

At a point above the jaws 11 the grippers are formed with outwardly projecting cam members 30, and there are provided on the casing 1 suitable cooperating projections 24-25 which, in the present instance, are formed by pressing opposed portions of the casing inwardly, the inner tube 3 being formed in its lower portion with suitable longitudinal slots 22-23 adapted to pass the projections 24-25. The projections 24-25 lie in the path with the cam members 30 and cooperate therewith to press the gripping jaws against the lead when the grippers are moved to their normal writing position by the spring 9.

The operation of my improved pencil takes place in the following manner:

In writing position the parts are at rest in the positions illustrated in Fig. 1, in which the grippers are pressed, in opposition to their inherent spring action, against the lead by reason of the contact between the cams 30 and the projections 24, 25, which force the ends 11 of the grippers inwards against the lead and to a position where the ends thereof will enter the cone shaped opening in the upper surface of the plate 8 forced upwards by the spring 9, and so be held in closed gripping position. The strength of the spring 9 is sufficient to cause a gripping action in excess of that required for writing. If now the cap 4, with the inner tube 3, is pushed downward, the collar 16 will push against the spring 18 which in turn pushes against the disk 17 on the sleeve 15 and pushes the sleeve and grippers 10-11 with the lead gripped therebetween downward; the plate 8 under the urge of the spring 9 keeps the grippers from opening until after the sleeve 15 strikes the limiting stop 13 on the tube 5. The propelling downward motion of the grippers, and consequently of the lead, then ceases, and a slight further downward motion of the sleeve 3, urged by pressure on the cap 4, brings the projections 20, 21, into contact with and then forces down the plate 8, permitting the grippers to spring apart and release their grip upon the lead. Pressure on the cap 4 then being released, the parts will move upward under the urge of the springs 9 and 18, the cams 30 will come into contact with the abutments 24, 25, and the grippers be forced inwards to the closed position, the plate 8 will slip over the ends thereof and lock them closed and the parts be again in normal writing position as illustrated in Fig. 1.

In order to reduce the danger of breaking the lead when pressure in excess of normal writing pressure is applied thereto, it is preferable to shape the projections 24 and 25, and to make the gripper legs 10 sufficiently flexible and the spring 18 sufficiently yieldable, so that the cams 30 will spring by the projections 24-25 and the gripping device and the lead will move upwardly within the pencil casing when excessive pressure is applied against the bottom of the lead. This upward movement will cause unusual compression of the spring 18, and so increase the tension thereof that when such excessive pressure against the lead point is removed the spring will cause the parts to resume their normal positions.

It will thus be seen that in the exemplified embodiment of the invention there are found a number of desirable features, including the provision of a gripping device which comprises a plurality of oppositely-disposed outwardly-resilient grippers which may be formed out of a single piece of spring metal and which are arranged so that they may be operated by the depression of the pencil cap. The grippers are under the particular control of a plate or disc, which, under the influence of a spring, serves to maintain the grippers in gripping engagement with the lead until downward movement of the grippers is limited by a stop, whereupon further movement of the plate against the pressure of its spring serves to permit the grippers to spring apart. The grippers are carried upwardly ahead of the plate or disc until they approach their normal upward position, and the clamping thereof by the recessed disc is facilitated by the provision of cooperating cam members on the grippers and on the casing. The clamping action of the recessed disc is maintained so as to hold the grippers in firm engagement with the lead until the disc is deliberately moved downwardly past the stop for the grippers by pressure applied to the cap of the pencil.

Since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which as a matter of language might be said to fall therebetween.

I claim:

1. In a magazine lead pencil, the combination of a two part tubular casing one part telescoping into the other, said casing having a magazine space in the upper part there-

- of and a discharge opening in its lower end; means for limiting the longitudinal movement of the telescoping part of said casing; a slotted guide tube mounted over said discharge opening, the upper end thereof forming a bottom for said magazine space; an opposed pair of resilient gripper legs, each with a cam projection thereon, pendent from a gripper sleeve mounted upon, and capable of limited longitudinal movement on said guide tube, the free ends of said legs converging toward each other and forming grippers; a spring supported member slidable on said guide tube and having a recess in the top thereof adapted to admit a portion of the converging grippers, the supporting spring always under tension and normally forcing said member against said converging grippers, and said grippers closed against a lead in said guide tube, and to their normal upward limit of travel; an abutment in the path of said gripper legs adapted to force said grippers closed, and to limit the upward movement thereof until sufficient force is added to that normally exerted by said supporting spring to cause said gripper legs to flex and the cams thereon to pass said abutment; a spring, the tension whereof will be increased by continued upward movement of the grippers beyond their normal upward limit, adapted to return said grippers to normal position when said additional force is removed; and means whereby the depression of the telescoping part of said casing will first force the grippers and the lead downward, then to further depress said member and permit said grippers to open and release the lead.
2. In a magazine lead pencil, the combination of a two part tubular casing one part telescoping into the other, said casing having a magazine space in the upper part thereof and a discharge opening in its lower end; means for limiting the longitudinal movement of the telescoping part of said casing; a slotted guide tube mounted over said discharge opening, the upper end thereof forming a bottom to said magazine space; an opposed pair of resilient gripper legs pendent from a gripper supporting sleeve mounted upon, and capable of limited longitudinal movement on said guide tube, the free ends of said legs converging toward each other and forming grippers adapted to enter the slots in said guide tube and grip a lead therein; a spring supported member slidable on said guide tube and having a recess in the top thereof adapted to receive a part of the converging grippers, said supporting spring normally forcing said member against said converging grippers, and said member closed against a lead in said guide tube, and at their upward limit of travel; an abutment in the path of the cams on said legs and adapted to contact therewith so as to force said grippers closed; and means whereby the longitudinal displacement of a part of said casing will first force said lead and grippers downward, then depress said member and permit the grippers to release their grip on the lead.
3. A pencil mechanism comprising a pair of resilient reciprocably mounted spring grippers naturally springing apart and adapted to be closed by coming in contact with an abutment, the free ends of said grippers converging toward each other; a spring actuated disk with a recess in the top thereof adapted to contact with the converging ends of said grippers, force them against an abutment adapted to force them toward each other, and to then hold them in closed position; and means connected with a part of the pencil casing whereby said disk may be depressed in opposition to its controlling spring until the grippers have been permitted to spring apart.
4. In a magazine lead pencil a pair of spring grippers resiliently and reciprocably mounted on a guide tube having longitudinal slots therein, an abutment in the path of said grippers adapted to force them closed, through said slots, when forced into contact therewith, a reciprocably mounted spring actuated disc adapted to contact with the ends of said grippers and to force, and hold them closed, the spring actuating said disk also adapted to force said grippers against said abutment.
5. In a magazine lead pencil, the combination of an outwardly spring pressed gripping device, a spring controlled disk adapted to force said gripping device into and hold it in intimate engagement with the lead, and means whereby the depressing of a cap connected to a part of the pencil casing will move the gripper and the lead downward and then cause said disk to release the grippers.
6. In a magazine lead pencil, a gripping and feeding device reciprocable on a lead guide tube; a spring tending to force said device upward, an abutment in the path of said device and adapted to close the grippers and to stop upward movement thereof until unusual upward pressure sufficient to flex a part of said device so that it will spring by said abutment, is applied thereto.
7. A pencil mechanism comprising a pair of oppositely-disposed resilient gripper legs dependent from a common support, their free ends converging towards each other but naturally springing apart, and formed into grippers curved to fit the lead; abutments adapted to contact with said gripper legs and force the grippers toward the lead, a spring-control plate with a recess therein adapted to receive the free ends of said grippers and to force and hold them closed, and means adapted to be actuated by the movement of a part of the pencil casing whereby said spring-const-

trolled plate may be depressed and the grippers permitted to open.

8. In a step-by-step pencil, the combination of a plurality of outwardly spring-pressed grippers adapted to grip and feed forward a lead in the pencil, an upwardly spring-pressed longitudinally-movable recessed member adapted normally to contact with said grippers and to thrust the grippers into gripping engagement with a lead and maintain them in such engagement, and means first to move said recessed member and said grippers downwardly as a unit and thereafter to carry said recessed member out of engagement with the grippers to allow them to spring apart.

9. In a step-by-step pencil, the combination of a plurality of longitudinally-movable outwardly-spring-pressed grippers, a longitudinally-movable clamping member adapted to bear against the outer surface of said grippers to clamp the same in gripping engagement with a lead in the pencil, resilient means acting normally to cause said clamping member to bear against said grippers, means to limit the downward movement of said grippers, and means to release the clamping action of said clamping member when the grippers reach their limit of downward movement.

- 10: In a step-by-step pencil, the combination of a plurality of outwardly resilient longitudinally-movable lead grippers, a longitudinally-movable collar, a spring arranged to press said collar upwardly against said grippers, means to move said collar downwardly and to compress said spring, said collar and said grippers being arranged in cam relation whereby said collar will normally clamp said grippers against a lead and will carry said grippers and the lead downwardly therewith, means to limit the downward movement of said grippers at a given point in the downward movement of said collar, said collar being adapted, after the downward movement thereof, to carry the grippers upwardly ahead of it under the influence of said spring.

11. In a step-by-step pencil, the combination of a plurality of longitudinally-movable lead grippers, means acting normally to hold said grippers in an upward position and in firm gripping engagement with a lead in the pencil, said holding means comprising a longitudinally-movable recessed member, means to move said recessed member and said grippers downwardly to advance the lead, a stop to limit the downward movement of said grippers, said moving means being adapted to carry said recessed member downwardly and out of operative engagement with the grippers after the grippers have reached said stop, and means to move said recessed member upwardly, said grippers being adapted to be carried upwardly ahead of said recessed

member and to be returned to gripping position only toward the end of the upward movement thereof.

12. In a step-by-step pencil, the combination of a plurality of longitudinally-movable lead grippers, resilient means tending to move the grippers out of engagement with a lead in the pencil, longitudinally-movable means acting normally to hold the grippers in a retracted position and in firm gripping engagement with the lead, and acting when moved in one direction to move the grippers downwardly a given distance and then to release its hold on the grippers, and when moved in the opposite direction to move said grippers upwardly and then to cause said grippers to be returned to a lead-gripping position.

13. A pencil mechanism comprising a longitudinally-movable gripper supporting member, a plurality of resilient arms extending from said supporting member, a lead-gripping jaw at the end of each arm, said arms tending to spread said jaws, a reciprocable member positioned beneath said jaws and formed with a recessed portion adapted to receive said jaws and to clamp the same against the lead, and means to reciprocate said reciprocable member and to cause said grippers to move downwardly therewith throughout a portion of its downward movement and to move upwardly ahead of the same.

14. In a step-by-step pencil, the combination of a plurality of outwardly spring-pressed longitudinally-movable lead grippers, a longitudinally-movable collar, the outer surfaces of said grippers and the inner surfaces of said collar being in cam relationship whereby said collar may impart a lead-gripping action to said grippers, and means for reciprocating said collar and for maintaining said collar in operative engagement with the grippers to feed a lead during the major portion of the downward movement of said collar and for carrying said grippers upwardly ahead of said collar during the major portion of the upward movement of the collar.

15. In a magazine lead pencil, the combination of a casing member, a reciprocable tube, means cooperating with said tube to provide a lead magazine, a spring positioned near the base of said casing member, a collar supported on said spring, a lead-gripping unit comprising a plurality of outwardly spring-pressed jaws adapted to be supported on said collar and to be normally thrust by said collar into engagement with a lead in the pencil, means adapted to cause downward movement of said collar upon the downward movement of said reciprocable tube, a stop to limit the downward movement of said gripping unit, and means including said col-

lar to carry the gripping unit downwardly with said collar until said unit reaches its limit of downward movement.

16. In a magazine lead pencil, the combination with a casing, means providing a lead magazine in the upper portion of the casing, and means to guide a lead from said magazine downwardly through the pencil, of a pair of members adapted to cooperate to feed a lead 70
- 10 in the pencil downwardly step-by-step, said members comprising respectively a plurality of outwardly-resilient lead grippers and a gripper-clamping element and each of said members being mounted for longitudinal movement, a longitudinally-movable exteriorly accessible element, means including said exteriorly accessible element to impart longitudinal movement to one of said members, said members being arranged so that the other of said members will normally partake of said movement, and means providing upper and lower stops for said other of said members, whereby said clamping element will release said grippers toward the 75 end of the downward movement of said exteriorly accessible element and will clamp the grippers against a lead toward the end of the upward movement of said exteriorly accessible element.
- 80 17. In a step-by-step pencil, the combination of means providing a tip, mechanism movable longitudinally of the pencil with respect to said tip, a plurality of longitudinally movable jaws arranged for the reception of a lead therebetween and reciprocable in response to the operation of said mechanism, means to limit the longitudinal movement of said jaws, means associated with said longitudinally movable mechanism for causing 85 said jaws normally to engage a lead in the pencil and for moving said jaws longitudinally between their limits of movement, and means to move said jaws out of engagement with the lead after they reach their limit of 90 downward travel, and means to operate said mechanism.
- 95 18. In a step-by-step pencil, the combination of a plurality of longitudinally movable jaws arranged for the reception of a lead 100 therebetween, means to limit the downward movement of the jaws, means for normally causing said jaws to grip a lead and for imparting longitudinal movement to the jaws, and means to move said jaws out of engagement with the lead after they reach their limit of 105 downward movement.
- 110 19. In a step-by-step pencil, the combination of lead-gripping and -feeding mechanism comprising a pair of longitudinally movable members adapted to cooperate to feed a lead downwardly step-by-step, said members comprising respectively outwardly spring-pressed gripper means and a gripper clamping element, a longitudinally movable exteriorly accessible element, means includ- 115
- 120 ing said exteriorly accessible element to impart longitudinal movement to one of said cooperating members, said cooperating members being arranged so that the other of said members will normally partake of said movement, and means providing a stop to limit the downward movement of said other of said cooperating members, said cooperating members being arranged so that the clamping element will release the gripper means to permit an immediate outward movement thereof when the downward movement of said other of said members is arrested by said stop.
- 125 20. In a step-by-step pencil, the combination of lead-gripping and -feeding mechanism comprising a pair of longitudinally movable members adapted to cooperate to feed a lead downwardly step-by-step, said members comprising respectively outwardly spring-pressed gripper means and a gripper clamping element, a longitudinally movable exteriorly accessible element, means including said exteriorly accessible element to impart longitudinal movement to one of said cooperating members, said cooperating members being arranged so that the other of said members will normally partake of said movement, means to limit the upward and downward movement of said other of said cooperating members, said cooperating members being arranged so that the clamping element will release the gripper means to permit an immediate outward movement thereof when the downward movement of said other of said cooperating members is arrested and will clamp said gripper means to assure immediate gripping action thereof when the upward movement of said other of said members is arrested.
- 130 21. In a step-by-step pencil, the combination of a plurality of longitudinally movable lead grippers, a spring-controlled longitudinally movable member adapted normally to hold said grippers in an upward position and in gripping engagement with a lead in the pencil and to maintain said grippers in gripping engagement with the lead during at least a part of their downward movement, means to move said grippers downwardly, and means to move the grippers out of engagement with the lead when in a downward position, said spring-controlled member being adapted to move said grippers upwardly ahead of itself while the same are out of engagement with the lead.
- 135 22. In a step-by-step pencil, the combination of a plurality of longitudinally movable lead grippers, means to limit the downward movement of said grippers, a spring-controlled longitudinally movable member adapted normally to hold said grippers in an upward position and in gripping engagement with a lead in the pencil and to maintain said grippers in gripping engagement during their downward movement, means to move 140

said grippers downwardly, and means to move the grippers out of engagement with the lead at the end of their downward movement, said spring-controlled member being adapted to move said grippers upwardly ahead of itself while the same are out of engagement with the lead.

23. In a step-by-step pencil, the combination of a plurality of longitudinally movable lead grippers, a spring-controlled longitudinally movable member adapted normally to hold said grippers in an upward position and in gripping engagement with a lead in the pencil and to maintain said grippers in gripping engagement with the lead during at least

a part of their downward movement, means to move said grippers downwardly, means to move the grippers out of engagement with the lead when in a downward position, said spring-controlled member being adapted to move said grippers upwardly ahead of itself while the same are out of engagement with the lead, and an exteriorly accessible actuating member, said spring-controlled member and said exteriorly accessible actuating member being independently mounted.

In testimony whereof I have affixed my signature.

EDWARD D. FELDMAN.
